UNITED STATES PATENT OFFICE

**HARRY BRADLEY ROWAN, OF NORTH ATTLEBORO, MASSACHUSETTS, ASSIGNOR TO
WHITING & DAVIS COMPANY, A CORPORATION OF MASSACHUSETTS**

DESIGN FOR METAL MESH FABRIC

Application filed June 3, 1930. Serial No. 35,891. Term of patent 14 years.

To all whom it may concern:

Be it known that I, HARRY BRADLEY Row-
AN, a citizen of the United States, residing at
North Attleboro, Bristol County, Massachu-
setts, have invented a new, original, and or-
namental Design for Metal Mesh Fabric, of
which the following is a specification, refer-
ence being had to the accompanying drawing,
forming part thereof.

Figure 1 is a plan view of a section
of metal mesh fabric showing my new de-
sign, the same comprising a multiplicity of

plates of the shape illustrated, in rows length-
wise and crosswise, connected together by
underlying parts which appear in the nar-
row spaces between adjacent plates.

Fig. 2 is a cross-sectional view of one of
the links of the metal mesh fabric connected
with the adjacent rings.

I claim:

The ornamental design for metal mesh
fabric as shown and described.

HARRY BRADLEY ROWAN.
